CLAIM

The ornamental design for a bracket light, as shown and described.

DESCRIPTION

FIG. 1 is a perspective view of a bracket light showing my new design;

FIG. 2 is a rear elevational view thereof;

FIG. 3 is a bottom plan view thereof;

FIG. 4 is a right side elevational view thereof;

FIG. 5 is a front elevational view thereof;

FIG. 6 is a left side view thereof;

FIG. 7 is a top plan view; and,

FIG. 8 is a perspective reference view thereof.
